US00D580960S

(12) **United States Design Patent**
Yamaguchi et al.

(10) **Patent No.:** **US D580,960 S**
(45) **Date of Patent:** **** Nov. 18, 2008**

(54) **NOZZLE FOR PLASMA CUTTING MACHINE**

(75) Inventors: **Yoshihiro Yamaguchi**, Nomi (JP);
Kazuhiro Kuraoka, Nomi (JP)

(73) Assignee: **Komatsu Industries Corporation**,
Ishikawa (JP)

(**) Term: **14 Years**

(21) Appl. No.: **29/300,890**

(22) Filed: **May 27, 2008**

(30) **Foreign Application Priority Data**

Apr. 24, 2008 (JP) 2008-010514

(51) **LOC (8) Cl.** **15-09**

(52) **U.S. Cl.** **D15/144**

(58) **Field of Classification Search** D8/70,

(57) **CLAIM**

The ornamental design for a nozzle for plasma cutting machine, as shown and described.

DESCRIPTION

FIG. 1 is a perspective view of a nozzle for plasma cutting machine showing our new design;

FIG. 2 is a front view thereof, a rear view being symmetrical to the front view;

FIG. 3 is a right side view thereof, a left side view being the same as the right side view;

FIG. 4 is a bottom plan view thereof;

FIG. 5 is a top plan view thereof; and,

FIG. 6 is a sectional view thereof taken along line 6—6 in FIG. 2.
